UNITED STATES PATENT OFFICE.

FELIX MEYER, OF NEW YORK, N. Y., ASSIGNOR TO BLANCK & COMPANY, INC., OF NEW YORK, N. Y., A CORPORATION OF NEW YORK.

DESIGN FOR LACE.

53,512.

Specification for Design.

Patented July 8, 1919.

Application filed May 5, 1919. Serial No. 294,996. Term of patent 3½ years.

To all whom it may concern:

Be it known that I, FELIX MEYER, a citizen of the United States, residing at New York, in the county of New York and State of New York, have invented a new, original, and ornamental Design for Lace, of which the following is a specification.

Said design consists in a lace pattern, as illustrated in the accompanying drawing, wherein the figure is a portion of a piece of lace showing my new design. The figure repeats indefinitely on the net in accordance with the length of the piece of lace.

What I claim as new is:

The ornamental design for lace as herein shown and described.

In witness whereof I have hereunto set my hand and seal at New York, New York, this 2nd day of May, A. D. nineteen hundred and nineteen.

FELIX MEYER. [L. S.]
